(57) **CLAIM**

The ornamental design for a work lamp, as shown and described.

DESCRIPTION

FIG. 1 is a left, rear, top perspective view of a work lamp showing our new design;

FIG. 2 is a right, front, bottom perspective view thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a left side elevational view thereof; and,

FIG. 8 is a right side elevational view thereof.

In the drawings, the broken lines illustrate portions of the work lamp that form no part of the claimed design.
